(57) **CLAIM**

We claim the ornamental design for a clamp for vacuum tube assemblies, as shown and described.

DESCRIPTION

FIG. 1 is a front perspective view of a clamp for vacuum tube assemblies showing our new design;

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a front perspective view thereof in an alternate position;

FIG. 9 is a front view thereof.

FIG. 10 is a rear view thereof.

FIG. 11 is a left side view thereof.

FIG. 12 is a right side view thereof.

FIG. 13 is a top view thereof; and,

FIG. 14 is a bottom view thereof.

The details shown in broken lines are for illustrative purposes only and form no part of the claimed design. Broken lines, if present in the drawings, are for illustrative purposes only and form no part of the claimed design.

1 Claim, 10 Drawing Sheets
